[57] CLAIM

The ornamental design for a desk top hanger for suspension-type document holders, substantially as shown and described.

DESCRIPTION

FIG. 1 is a perspective view of a desk top hanger for suspension-type document holders embodying my new design;

FIG. 2 is a left side elevational view;

FIG. 3 is a front elevational view;

FIG. 4 is a top plan view; and

FIG. 5 is a bottom plan view.
